UNITED STATES PATENT OFFICE.

HENRY E. BUTLER, OF SCHENECTADY, NEW YORK, ASSIGNOR TO GENERAL ELECTRIC COMPANY, A CORPORATION OF NEW YORK.

RENEWABLE FUSE.

Application filed September 17, 1921. Serial No. 501,304.

To all whom it may concern:

Be it known that I, HENRY E. BUTLER, a citizen of the United States, residing at Schenectady, county of Schenectady, State 5 of New York, have invented certain new and useful Improvements in Renewable Fuses, of which the following is a specification.

The present invention relates to fuses such as are used to protect electrical machinery and has for its object to provide an improved structure and arrangement in a fuse whereby the same can be readily renewed whenever it is burned out. A further object of my invention is to provide an arrangement whereby it is insured that when a fuse is renewed, it will be renewed with fuse material similar to that burned out so there will be no danger of renewing the fuse with fuse wire of too great or too little current-carrying capacity.

For a consideration of what I believe to be novel and my invention, attention is directed to the accompanying description and the claim appended thereto.

My invention is well adapted for use in connection with fuses used to protect the windings of transformers and I have specifically illustrated and described it as applied to this use. It will be understood, however, that it is not necessarily limited thereto.

In the drawing, Fig. 1 is a sectional view of a transformer fuse embodying my invention; Fig. 2 is a sectional view taken at a 35 right angle to Fig. 1; Fig. 3 is a perspective view of a magazine fuse; Fig. 4 is a perspective view of a modified form of magazine fuse; and Fig. 5 is a perspective view of contacts of a fuse showing the magazine 40 fuse of Fig. 3 connected thereto.

Referring to the drawing, 10 indicates a housing made of suitable insulating material, such as porcelain, and provided with openings 11 to receive screws or bolts for fastening it to a support. In housing 10 is a ledge 12 on which are fixed two line contacts A and B alike in structure and arranged diagonally opposite each other. As shown in perspective in Fig. 5, each contact comprises a base 13 which lies against ledge 12 and is fastened thereto by a suitable screw 14 extending through hole 14^a. On base 13 is a head 15 provided with a passage 16 which stands in line with a hole 17 in housing 10 and which is adapted to re-

ceive the end of an electrical conductor wire. In head 15 are set screws 18 for fastening a conductor end in passage 16. Base 13 is provided with an angular extension 19 under which lies the central portion of a 60 U-shaped spring contact 20 which is fastened thereto by a screw 21. The ends of contact 20 are bent inwardly on themselves to provide a pair of spaced spring fingers 22 adapted to receive a contact blade between 65 them. Adjacent one edge of contact 20 is a spring-locking plate 23 having a vertically extending slot 24, at the lower edge of which is a struck-out lip 25. Plate 23 is fixed in position by an angular extension 26 which 70 is fastened under the head of screw 14.

The fuse and contact blades for connecting together contacts A and B are carried by a member made of insulating material and comprising a head 30 provided on one 75 side with a knob 31 and on the other side with a long nose 32 having longitudinally extending ribs 33 on its sides which form a groove extending up one side of the nose, across its top and down the other side. 80 Nose 32 is adapted to enter housing 10 and the groove on it is adapted to receive a fuse wire or ribbon. At the base of nose 32 on opposite sides of it are fixed two contact blades 35 and 36 adapted to engage spring 85 contacts 20. Blades 35 and 36 are fastened in position by integral angular extensions 37 and 38 which lie against the sides of nose 32 and are held by screws 37^a and 38^a. In the ends of extensions 37 and 38 are binding 90 screws 39 and 40. Contact blades 35 and 36 are each provided with beveled edges 41 which terminate in curved shoulders 42 and when the blades are moved into engagement with contacts 20 the beveled edges 41 ride 95 along the ends of spring-locking plates 23 putting them under tension so that when shoulders 42 reach slots 24 the spring plates will snap over the shoulders as shown at the right-hand side of Fig. 1 thus locking the 100 contact blades in engagement with the spring contacts. It will be clear that when contact blades 35 and 36 are connected by a fuse wire and are brought into engagement with line contacts A and B a circuit will be 105 closed through the fuse.

My invention relates particularly to the fuse arrangement and in carrying it out I provide a suitable casing or magazine 45 in which is a roll of fuse material 46 of suffi- 110

cient length to form a number of fuses. Fuse material 46 may be flat, i. e., in the form of ribbons, as shown in Fig. 3, or it may be round as shown in Fig. 4. Magazine 45 is made of suitable metal and is located below contact screw 39 and preferably directly adjacent head 30. It is fixed in place by an integral extension 47 which extends across extension 37 and is provided with a hole 48 through which screw 39 passes. Under the head of screw 39 and on top extension 47 is a clamping plate 49 between which and extension 47 a fuse ribbon or wire may be clamped by screw 39 and under the head of screw 40 is a similar clamping plate 50 between which and extension 38 a fuse ribbon or wire may be clamped by screws 40. Plates 49 and 50 have suitable holes through which screws 39 and 40 extend.

The housing 10 and contact arrangement therein, and head 30 which carries the fuse wire or ribbon and the contact blades thereon is a known arrangement in extensive use in connection with transformers. To apply my invention thereto it is only necessary to remove binding screw 39, put a magazine fuse casing with a roll of fuse material therein in place with extension 47 lying over extension 37 and replace screw 39. Sufficient fuse wire or ribbon is now unwound from the roll by pulling on the end of it to reach over the end of nose 32 and down to contact blade 35. The free end of the fuse material is now fastened between clamping plate 50 and extension 38 by loosening binding screw 40, slipping the end of the fuse material between the plate and extension and tightening again the screw. The fuse material adjacent casing 45 is fastened between extension 47 and clamping plate 49 by slipping it between the two and tightening binding screw 39. If now the fuse blows, it is only necessary to remove head 30 from casing 10, loosen screws 39 and 40, pull out a new length of fuse material from the roll, fasten it to the contact blades by tightening again screws 39 and 40, and replace the head again. This is a simple operation, easily and quickly performed and requires the use of only a screw driver. The roll may contain sufficient fuse material for a number of renewals and when entirely used, a new magazine can be quickly installed.

It will be seen that the arrangement is such that the current does not pass through the roll of fuse material so there is no danger of its becoming fused. And it is not likely to become damaged when a fuse blows for in general the parting of the fuse takes place at the end of nose 32. But in any event, the fuse magazine is sufficiently

far from clamping plate 49 to insure that the roll of fuse material would not be injured should the fuse part directly adjacent 65 such plate.

One of the difficulties heretofore experienced in actual use with fuses of this general character has been that an attendant was likely to replace a blown fuse with any 70 fuse material he might have at hand irrespective of its carrying capacity; or failing to have a piece of fuse material handy, he would put in a piece of ordinary wire. As a result electrical apparatus has often been 75 burned out because of the use of improper fuse material. With my invention this difficulty is obviated because there is always present a supply of fuse material of proper carrying capacity and the simplest and easiest thing is to renew the fuse with it.

My invention may be readily adapted and applied to existing structures with but slight changes if any, no change whatever in existing structures being required in the particular case illustrated.

In accordance with the provisions of the patent statutes, I have described the principles of operation of my invention, together with the apparatus which I now consider to 90 represent the best embodiment thereof; but I desire to have it understood that the apparatus shown is only illustrative, and that the invention may be carried out by other means.

What I claim as new and desire to secure by Letters Patent of the United States, is,—

In combination, a housing open at one end and closed at the other end to form a socket, contacts at the mouth of the socket, a fuse-carrying member comprising a head and a nose, contacts fixed to the fuse-carrying member adjacent to its head for engagement with the socket contacts, binding posts carried by said contacts, a closed receptacle having a supply of fuse material therein, said receptacle being provided with a slot through which the end of the fuse material extends, and means fastening said receptacle to the fuse-carrying member adjacent to one of the contacts thereon and outside it as regards the flow of current whereby fuse material from said receptacle may be supplied for fastening to such contact and extending therefrom over said nose to the other contact on the fuse-carrying member, the fuse material in the receptacle being outside the electric circuit when the fuse-carrying member is inserted into the socket to bring its contacts into engagement with the housing contacts.

In witness whereof, I have hereunto set my hand this 16th day of September, 1921.

HENRY E. BUTLER.
